PULVERIZING AND SEPARATING MACHINE.

1,159,122.

Specification of Letters Patent.

Patented Nov. 2, 1915.

Application filed May 9, 1912. Serial No. 696,061.

To all whom it may concern:

Be it known that I, EDWARD J. STECKLE, a citizen of the United States, residing at Dixon, in the county of Lee and State of Illinois, have invented a certain new and useful Improvement in Pulverizing and Separating Machines, of which the following is a specification.

My invention relates to improvements in pulverizing machinery and has for its object to provide a new and improved means for finely reducing or crushing material and to provide means for separating material so crushed by means of an air separating system which shall be accurate, durable and reliable.

It is illustrated diagrammatically in the accompanying drawing, wherein is shown a side in part section with parts broken away. The open base A which carries the bearings A¹, A² supports the annular ring or frame A³ having the closed bottom A¹¹ and centrally located upwardly extending hollow cylinder A⁵. The crushing ring A⁶, having the inwardly disposed spherically curved surface A⁷, rests upon the flange A⁸ adjacent the long edge of the frame A³ and is held in position by the flange A⁹ from which projects upwardly the frame A¹⁰. The shaft B is rotatably mounted in the bearings A¹, A² and in a bearing B¹ supported at the top of the frame A¹⁰. The pulley B² is keyed to the shaft B between the bearings A¹, A² and the said shaft carries rigidly attached thereon the hollow downwardly depending sleeve B³ which supports the sleeve A⁵. The driving spider B⁴ is mounted on the sleeve B³ and carries the pushers B⁵ in engagement with the balls B⁶, which balls are forced outwardly by centrifugal force against the curves A⁷ and are supported at their bottom by the flange B⁷ projecting inwardly from the ring A⁶. The arms B⁸, which project upwardly from the spider or pusher B⁴, carrying the inclined vanes or fans B⁹.

The conical hood C which is supported by the frame A¹⁰ is provided with the upwardly extending cylindrical extension C¹ in which is located the fixed sleeve C³ communicating with the exhaust pipe C⁴ and carrying the slidably mounted sleeve C⁵. The screw conveyer C⁶ is supported by the conical hood C at the other end of the frame

A¹⁰ and discharges by means of the spout C⁷ downwardly toward the crushing zone being fed from any suitable supply source not indicated. The spiral conduit C⁸ which is disposed about the outer portion of the conical hood C and is of constantly increasing cross sectional area communicates with the interior of the hood by the inclined passage ways C⁹ which discharge downwardly toward the crushing zone. The discharge conduit X which leads from the top of the conical hood or separating chamber C discharges into any suitable dust and air separator not shown the air from which is discharged back into the spiral conduit C⁸ and thence to the conical chamber by any suitable means not shown.

The conical deflector D whose apex points upwardly toward the top of the conical hood C carries the truncated conical baffle wall D¹ extending upwardly, this wall being attached to the cone D by the angles D². The straps D³ arranged about the outer edge of the wall D¹ suspend it and the conical baffle from the top C² being provided with perforations D⁴ in opposition to perforations D⁵ in the hangers D⁶ riveted to the top bolts D⁷ engaging the perforations in the straps and hangers and may be positioned so as to vary the height at which the baffle and conical wall is suspended. The conical wall D is concentric with but separated from the baffle plate D¹, thus forming an annular passageway D⁸ between them. A flexible skirt sleeve or trap D⁹ of fabric or other suitable material which will prevent the upward passage of the air through this annular channel, but which will swing clear to permit the downward passage of the material along the surface of the cone D, is suspended from the conical wall and hangs down toward the cone D in such manner that its lower edge rests upon the cone or deflector D. Thus the column of air passing upwardly through the chamber is compelled to pass around the annular wall D¹, but the material deposited upon the upper surface of the annular wall D¹ or the cone D may pass freely back into the lower portion of the chamber.

I have not deemed it necessary to indicate the means for separating the dust and the air after they have been discharged together from the crushing and separating

chamber because any suitable means can be used without affecting in any way my device.

It will be evident that while I have shown in my drawing an operative device still many changes might be made in size, shape and arrangement of parts without departing materially from the spirit of my invention.

10 The material to be crushed or pulverized is fed to the machine by the screw conveyer, which discharges it into the hood above the rotating fans. This material, of course, drops down into the crushing zone and is 15 there pulverized between the crushing ring or the rotating balls which are held centrifugally against the ring by centrifugal force to enable them to perform this crushing action. A blast of air is driven by 20 means not shown through the passages here illustrated into the spiral conduit or passage surrounding the hood C and this blast of air is discharged through the passages interposed between this spiral conduit and the 25 interior of the hood C. The blast of air is by the arrangement and proportion of the parts compelled to discharge substantially equally at all points about the circumference of the crushing zone and passes across the top of 30 the crushing zone, coming in contact with the crushed material as it is violently agitated by the crushing balls. This blast or air current will pick up from the crushing surfaces of the zone these finer particles of 35 the reduced material which have been sufficiently reduced and leave for further crushing the heavier particles too heavy or too large to be acted upon adequately by the air blast. The fans or vanes above the crushing 40 zone also assist in this process. The suction of the air thus picks up the loose particles and carries them up along the conical sides of the separating chamber, past the edge of the conical baffle and up and around the inverted conical wall and thence out through 45 the discharge passage. The size of material carried out from the chamber depends on the position of the slideable sleeve E³. If the sleeve E³ extends down far into the chamber, only small particles will be carried out. If the sleeve does not extend quite so far into the chamber, larger particles will be carried out. In any event, the particles picked or thrown up from the crushing zone 50 and carried up into the housing will a great many of them be too big to be carried by the air current out by the top of the baffle and then up through the passage and these particles will drop down into the conical baffle. 55 They will slide down to push the valve flap to one side and pass from between it and the conical wall and thence drop back into the crushing zone. These particles, having lost their momentum, will pass down through 60 the air blast and be swept clean of any fine 65

particles adhering to them. Thus they will return to the crushing zone ready to be further reduced.

The slideably mounted sleeve as indicated above the baffle plate provides means for adjusting the size of the particles by controlling and varying the length of the path followed by the air and also by varying the direction of travel. It will be evident that under ordinary circumstances most of the 75 adjustment as to size of the particles will be done by varying the rate of feed to the mill and by varying the amount of air passing through the separator and mill. The arrangement of the air duct or passage leading 80 from the separator to the mill is such that the velocity and amount of air fed to the mill at any point thereabout is substantially equal to that at any other point, this being done by decreasing the cross sectional area 85 of the air passage as it encircles the mill.

It will be evident that by the arrangement shown I am no longer dependent upon the usual separating screen which has a tendency to wear out and permit ever increasing 90 sizes of particles to pass through and at the same time has a tendency to become stopped up when moist or sticky materials are used.

I claim:

1. A deflector comprising two cones, one 95 upright, the other inverted, truncated and mounted on but spaced from the upright cone, the truncated cone extending upwardly above the upper surface of the upright cone and projecting outwardly beyond its base, 100 the lower edge of the truncated cone being located adjacent the lower edge of the surface of the upright cone and yielding means comprising an annular flexible wall mounted about the lower edge of the truncated cone 105 depending downwardly therefrom and resting upon the upper surface of the upright cone adjacent its lower edge to close the space between the cones, said wall being free to open outwardly and downwardly to permit 110 the passage of material downwardly along the surface of the upright cone, but held against inward movement by its contact along its lower edge with the upright cone.

2. The combination with a deflector comprising two cones mounted one upon the other and an annular space between them of yielding means comprising a flexible wall mounted about the lower edge of one of said cones and depending downwardly therefrom 115 and resting upon the upper surface of the other for closing the space between them.

3. A deflector comprising two cones, one upright, the other inverted, truncated and mounted on but spaced from the upright 120 cone, the truncated cone extending upwardly above the upper surface of the upright cone and projecting outwardly beyond its base, the lower edge of the truncated cone being located adjacent the lower edge of the sur- 125 130

face of the upright cone and yielding means for closing the space between the cones.

4. A deflector comprising two cones, one upright, the other inverted, truncated and mounted on but spaced from the upright cone, the truncated cone extending upwardly above the upper surface of the upright cone and projecting outwardly beyond its base, the lower edge of the truncated cone being located adjacent the lower edge of the surface of the upright cone and yielding means comprising an annular wall for closing the space between the cones.

5 cone, the truncated cone extending upwardly above the upper surface of the upright cone, and projecting outwardly beyond its base, 70 the lower edge of the truncated cone being located adjacent the lower edge of the surface of the upright cone and yielding means comprising an annular flexible wall mounted about the lower edge of the truncated cone depending downwardly therefrom and resting upon the upper surface of the upright cone adjacent its lower edge for closing the space between the cones.

10 75

5. A deflector comprising two cones, one upright, the other inverted, truncated and mounted on but spaced from the upright cone, the truncated cone extending upwardly above the upper surface of the upright cone and projecting outwardly beyond its base, the lower edge of the truncated cone being located adjacent the lower edge of the surface of the upright cone and yielding means comprising an annular flexible wall for closing the space between the cones. 15

10. A deflector comprising two cones, one upright, the other inverted, truncated and mounted on but spaced from the upright cone, the truncated cone extending upwardly above the upper surface of the upright cone and projecting outwardly beyond its base, the lower edge of the truncated cone being located adjacent the lower edge of the surface of the upright cone and yielding means comprising an annular flexible wall mount- 20 25 30 35 40 45 50 55 60 65 70 75 80 85 90 95 100

25 6. A deflector comprising two cones, one upright, the other inverted, truncated and mounted on but spaced from the upright cone, the truncated cone extending upwardly above the upper surface of the upright cone and projecting outwardly beyond its base, the lower edge of the truncated cone being located adjacent the lower edge of the surface of the upright cone and yielding means comprising an annular flexible wall mounted about the lower edge of the truncated cone for closing the space between the cones.

30 7. A deflector comprising two cones, one upright, the other inverted, truncated and mounted on but spaced from the upright cone, the truncated cone extending upwardly above the upper surface of the upright cone and projecting outwardly beyond its base, the lower edge of the truncated cone being located adjacent the lower edge of the upper surface of the upright cone and resting upon the upper surface of the upright cone adjacent its lower edge to close the space between the cones, said wall being free to open outwardly.

35 8. A deflector comprising two cones, one upright, the other inverted, truncated and mounted on but spaced from the upright cone, the truncated cone extending upwardly above the upper surface of the upright cone and projecting outwardly beyond its base, the lower edge of the truncated cone being located adjacent the lower edge of the upper surface of the upright cone and resting upon the upper surface of the upright cone adjacent its lower edge to close the space between the cones, said wall being free to open outwardly.

7. A deflector comprising two cones, one upright, the other inverted, truncated and mounted on but spaced from the upright cone, the truncated cone extending upwardly above the upper surface of the upright cone and projecting outwardly beyond its base, the lower edge of the truncated cone being located adjacent the lower edge of the surface of the upright cone and yielding means comprising an annular flexible wall mounted about the lower edge of the truncated cone depending downwardly therefrom and resting upon the upper surface of the upright cone adjacent its lower edge to close the space between the cones, said wall being free to open outwardly and downwardly. 110

40 45 50

12. A deflector comprising two cones, one upright, the other inverted, truncated and mounted on but spaced from the upright cone, the truncated cone extending upwardly 115

8. A deflector comprising two cones, one upright, the other inverted, truncated and mounted on but spaced from the upright cone, the truncated cone extending upwardly 55 above the upper surface of the upright cone and projecting outwardly beyond its base, the lower edge of the truncated cone being located adjacent the lower edge of the surface of the upright cone and yielding means 60 comprising an annular flexible wall mounted about the lower edge of the truncated cone depending downwardly therefrom and resting upon the upper surface of the upright cone for closing the space between the cones. 65

120

125

130

65 9. A deflector comprising two cones, one upright, the other inverted, truncated and

5 mounted on but spaced from the upright cone, the truncated cone extending upwardly above the upper surface of the upright cone and projecting outwardly beyond its base, the lower edge of the truncated cone being located adjacent the lower edge of the surface of the upright cone and yielding means comprising an annular flexible wall mounted about the lower edge of the truncated cone depending downwardly therefrom and resting upon the upper surface of the upright cone adjacent its lower edge to close the space between the cones, said wall being free to open outwardly and downwardly to 10 permit the passage of material downwardly.

15 14. A deflector comprising two cones, one upright, the other inverted, truncated and mounted on but spaced from the upright cone, the truncated cone extending upwardly above the upper surface of the upright cone and projecting outwardly beyond its base, the lower edge of the truncated cone being located adjacent the lower edge of the surface of the upright cone and yielding means 20 comprising an annular flexible wall mounted about the lower edge of the truncated cone depending downwardly therefrom and resting upon the upper surface of the upright cone adjacent its lower edge to close the space between the cones, said wall being free to open outwardly and downwardly to 25 permit the passage of material downwardly along the surface of the upright cone.

30 15. A deflector comprising two cones, one upright, the other inverted, truncated and mounted on but spaced from the upright cone, the truncated cone extending upwardly above the upper surface of the upright cone and projecting outwardly beyond its base, the lower edge of the truncated cone being located adjacent the lower edge of the surface of the upright cone and yielding means comprising an annular flexible wall mounted 35 40

about the lower edge of the truncated cone depending downwardly therefrom and resting upon the upper surface of the upright cone adjacent its lower edge to close the space between the cones, said wall being free to open outwardly and downwardly to permit the passage of material downwardly along the surface of the upright cone, but held against inward movement.

16. A deflector comprising two cones, one truncated, and mounted on the other but spaced therefrom, and yielding means for closing the space between them, the truncated cone extending upwardly above the upper surface of the other cone, the closing means comprising a flexible valve ring mounted about the lower edge of the truncated cone and depending downwardly upon the former cone. 60

17. The combination with a separating chamber of means for feeding air and dust upwardly from the bottom thereof, means for withdrawing them from the top thereof, a deflector located intermediate said means extending across the separating chamber and in the path of the air current, said deflector being smaller in cross sectional area than the separating chamber located substantially in a plane perpendicular to the central axis of the chamber and the normal path of the air and comprising a conical baffle plate the apex of which points upward, a truncated conical guard concentric with said baffle plate and mounted thereon but spaced therefrom and an air trap to close said space against the upward movement of the air. 70 75 80

Signed at Dixon, Illinois, this second day
of May 1912.

EDWARD J. STECKLE.
